VENDING MACHINE FOR BOOKS, MAGAZINES
OR THE LIKE

Hubert M. Giepen, Chicago, Ill., assignor to General
Vending Corporation, Kenosha, Wis., a corporation of Wisconsin

Filed Oct. 3, 1963, Ser. No. 76,850
Term of patent 14 years
(Cl. D52—3)

FIG. 1 is a front elevational view of a vending machine for books, magazines or the like, embodying my new design.

FIG. 2 is a side view of the vending machine shown in FIG. 1.

The undisclosed side is the same as the side shown, and the top and rear of the vending machine are plain in appearance.

I claim:

The ornamental design for a vending machine for books, magazines or the like, substantially as shown and described.
